UNITED STATES PATENT OFFICE.

HENRY L. EINSTEIN, OF BOUND BROOK, NEW JERSEY, ASSIGNOR TO THE
BOUND BROOK WOOLEN MILLS, OF SAME PLACE.

DESIGN FOR CLOTH.

SPECIFICATION forming part of Design No. 14,568, dated January 20, 1884.

Application filed November 3, 1883. Term of patent 7 years.

To all whom it may concern:

Be it known that I, HENRY L. EINSTEIN, a citizen of the United States, and a resident of Bound Brook, in the State of New Jersey, have 5 invented and produced a new and original Design for Cloths, of which the following is a specification.

My design consists in producing parallel bands or sections on the cloth, upon the surface of which there are "pills," "knots," or "waves," differing in size.

My design is illustrated by the accompanying drawings, in which Figure 1 shows a top view of a piece of my cloth, and Fig. 2 a sectional view of the same. *a a a* are the bands having the large pills or knots. *b b b* are the adjacent bands having the smaller pills or knots.

In Fig. 2 the difference in elevation between the bands *a* and *b* is seen.
20 *c c c* represent grooves cut in the nap, as

usual, to line off such cloths. These grooves when used, may run between the bands to more closely define and separate them, but they do not constitute a material part of my design, 25 and may be omitted, if preferred; and I do not limit myself to cloths in which the bands run longitudinally.

I claim—

The design for the surface of long-nap 30 cloths, as herein shown and described, the same consisting in parallel bands having pills, knots, or waves thereon larger than the pills, knots, or waves on the adjacent bands, substantially as set forth.

Signed at Bound Brook, in the county of Somerset and State of New Jersey, this 30th day of October, A. D. 1883.

HENRY L. EINSTEIN.
